UNITED STATES PATENT OFFICE.

WILLIAM HALE, OF CARLTON, NEAR MELBOURNE, VICTORIA, AUSTRALIA.

SCRUBBING OR CLEANING BRUSH.

Application filed September 26, 1924, Serial No. 740,093, and in Australia October 12, 1923.

This invention has reference to scrubbing or cleaning brushes and has for its object the provision of means for detachably combining a block or bar of soap with said device enabling the user to control the quantity of soap used in the scrubbing or cleaning operation and to prevent the laborious task of imparting a soapy film to the surface of the brush or other cleaning device, by rubbing said surface with the soap or other cleaning medium in order to provide said brush with the necessary quantity thereof.

But in order to more readily understand the invention reference will now be made to the accompanying drawings in which:—

Figure 1 is a sectional view of a brush constructed according to this invention.

Figure 2 is a similar view showing soap block in operative position.

Fig. 3 is a view showing the soap holder in end elevation.

Figure 4 is a sectional elevation of said soap holder.

Fig. 5 is a detail view showing the use of the pivots of the spring control plate as a securing means.

According to this invention the brush stock 5 is formed at one or both ends with an opening adapted to receive a metal holding device which may be detachably affixed to said stock.

This holding device consists essentially of a rectangular shell 6 formed on the upper portion with a flanged or rolled edge 7 adapted to engage the upper surface 8 of the brush stock 5 and near one end of said shell 6 is mounted a spring controlled plate 9 which is positioned in the shell 6 and adapted to hold the soap block 10 in position by exerting pressure against the side thereof so that it may not slip through and will always be in constant engagement with the surface being cleaned.

The shell 6 is held in position on the brush stock 5 by means of screws or other fastening devices which pass through extensions 11—12 formed on the ends of the pivot pin 13 of the spring controlled plate 9.

Disposed behind the plate 9 is a spring 14, one end of which is secured to said plate and the other end to the brush stock 5 by means of a screw 15 which passes into the stock 5.

When in use the soap block 10 is positioned within the shell 6 and if desired the soap block 10 may project beyond the upper

surface of the brush stock 5 so that the necessity of frequent changing of soap is eliminated to a certain extent.

The soap block 10 when in use is pressed through the opening of the brush stock until it takes the same plane as the scrubbing surface of the bristles 16 when the scrubbing or cleaning operation may be proceeded with.

As the soap wears down the pressure of the finger on top of the soap block 10 is sufficient to cause it to drop or slide downwardly within the shell 6 already described and immediately the pressure is released from said soap the spring plate 9 herein described holds the soap block 10 in position out of line with the surface until further pressure is applied when it moves to the surface to be scrubbed.

On the insertion of the soap 10 into the shell 6 said soap and shell rise clear of surface contact as shown by dotted line, Figure 2, by the action of the spring 14 which also serves to hold the soap 10 within the shell 6, the soap 10 being assisted to retain its position in the shell by forming a bead 6^a near the lower edge of the shell.

When it is desired to impart a soapy film to the surface being scrubbed the finger of the user is pressed on the soap block 10 and when the finger is released therefrom the soap 10 and shell 6 rise clear of surface contact.

A latch 9' is mounted on the brush stock 5 to overlie and hold the soap block. This latch is of Z-form with the lower portion pivotally mounted on the block and the upper portion elevated so that it may be readily turned to a position to overlie the rim of the shell 6 and project inwardly of the same to overlie the soap block, as shown in Fig. 1. The pivotal mounting of the latch 9' permits it to be turned away from operative position, as shown in Fig. 2.

This is an important feature in this invention.

Therefore the invention consists essentially of forming an opening or openings in a brush stock 5 adapted to receive a metal shell 6 provided with a spring plate 9 to hold the soap.

What I claim as my invention and desire to secure by Letters Patent is:—

1. A brush having a stock formed with an opening, a metal shell secured within the opening and having an upper marginal edge

resting upon the upper surface of the stock, and a spring pressed plate pivotally mounted within the shell, the pivot means for the plate being extended through the 5 walls of the shell and overlying and bearing upon the upper surface of the stock to provide means by which said pivot may be secured to the stock.

2. A brush stock formed with an opening 10 therethrough, a soap receiving shell arranged in said opening, said shell having a length exceeding that of the soap block to be inserted therein, and means pivotally mounted in one end of the shell to exert a 15 raising pressure on the proximate end of the soap block, whereby to permit the soap

block to be depressed under pressure thereon tending to displace said pivoted means.

3. A scrubbing brush having a stock formed with an opening therethrough, a 20 metal shell adapted to be secured in said opening and to accommodate a soap block, a plate pivotally mounted in the shell with its operative end adapted to engage the soap block, and a spring between said plate 25 and shell to permit pressure on said soap block to displace the plate against the tension of the spring.

Signed at Melbourne, Victoria, Australia, this 10th day of March, 1924.

WILLIAM HALE.
